UNITED STATES PATENT OFFICE

154,952

DESIGN FOR AN ILLUMINABLE SIGN CASING

Lewis E. Peters, Beverly Shores, Ind., assignor to
Raymond M. Price and associates, Inc., Chester-
ton, Ind., a corporation of Indiana

Application September 2, 1948, Serial No. 148,435

Term of patent 14 years

(Cl. D1—12)

To all whom it may concern:

Be it known that I, Lewis E. Peters, a citizen of the United States, residing at Beverly Shores, in the county of Porter and State of Indiana, have invented a new, original, and ornamental Design for an Illuminable Sign Casing, of which the following is a specification, reference being had to the accompanying drawings, forming part thereof, wherein:

Figure 1 is a front elevational view of an illuminable sign casing showing my new design;

Figure 2 is a side elevational view;

Figure 3 is a rear elevational view; and

Figure 4 is a top plan view.

I claim:
The ornamental design for an illuminable sign casing, as shown.

LEWIS E. PETERS.
